UNITED STATES PATENT OFFICE.

ANNE A. DONHAM AND ISAAC D. PEARCE, OF KANSAS CITY, MISSOURI;
SAID PEARCE ASSIGNOR TO SAID DONHAM.

NON-REFILLABLE BOTTLE.

SPECIFICATION forming part of Letters Patent No. 725,944, dated April 21, 1903.

Application filed October 20, 1902. Serial No. 128,037. (No model.)

To all whom it may concern:

Be it known that we, ANNE A. DONHAM and ISAAC D. PEARCE, citizens of the United States, residing at Kansas City, in the county 5 of Jackson and State of Missouri, have invented new and useful Improvements in Non-Refillable Bottles, of which the following is a specification.

Our invention relates to non-refillable bottles, the object of our invention being to provide a bottle for sauces, medicines, perfumes, liquors, &c., which cannot be filled a second time without fracturing the neck of the bottle or its stopper.

Referring now to the accompanying drawings, Figure 1 is a central vertical section of a non-refillable bottle embodying our invention. Fig. 2 is a top plan view of the baffle-plate, the walls about said plate being sectioned on line *a b* of Fig. 1. Fig. 3 is a top plan view of the upper cup-shaped valve. Fig. 4 is a bottom plan view of the plug which forms the seat for the upper valve. Fig. 5 is a top plan view of the lower valve.

Cemented within the neck of the bottle (after the filling of the bottle) is a tubular plug 1, which may be of metal, glass, or any suitable material. The upper end of said plug is adapted to receive a cork. An annular flange 2, integral with said plug, rests on the mouth of the bottle. Across the upper portion of said plug, integral therewith, is a baffle-plate 3, having ports 4 therein for the passage of liquid. The portions 5 between 35 said openings connect the body of said plate with the plug 1. The section in Fig. 1 is taken through two of the ports 4 in said plate. A short distance below said plate 3 the plug 1 is provided with an internal annular flange 6, the upper portion of which is broader (not thicker) than the lower portion thereof, as shown in Fig. 1. The purpose of this flange 40 is to make it more difficult to hold open the valve 13 with a wire to cause liquid poured into the bottle to flow mainly into the cavity in said valve and to limit the opening movement of said valve.

Fitted within the lower end of the plug 1 is a small tubular plug 7, having an external 45 annular flange 8, which underlies the bottom of the larger plug 1. The lower portion of

plug 7 forms a crenelated flange, which is divided into alternate projections 9 and recesses 10, as shown. These recesses 10 form ports for the efflux of liquid from the bottle when 55 the lower valve 12 is unseated by tipping the bottle. The main (upper) valve 13 rests upon the upper inner edge of plug 7. In external form said valve is cylindrical, except that its outer face is cut by a plurality of vertical 60 flutes or grooves 14 and its lower end is approximately conical in shape. Within this valve is a cylindrical chamber 15, which is made as large as possible in order that it will receive a greater volume of any liquid than 65 would pass into the grooves 14 of the valve. The upper end of this valve is about one-sixteenth of an inch below the bottom of the aforesaid internal flange 6 of plug 1.

Fitted between a recess provided around 70 the lower portion of plug 1 and the neck of the bottle is a cup-shaped piece 17, at the bottom of which is an inwardly-projecting flange 18, which forms a seat for a disk valve 12. Said valve 12 is flat beneath, and its upper 75 face is mainly flat, but is slightly concaved, as shown. In the periphery of this valve are several recesses or ports 19, adapted to pass liquid from the bottle. The purpose of this valve operating in connection with 80 the upper valve 13 is to render any refilling process more ineffectual.

In assembling the above-named parts the cupped valve 13 is slipped into the plug 1, and the valve-seat plug 7 is then inserted in 85 the lower end of said plug and secured by cement or otherwise. The lower valve 12 is dropped into cup 17, into which the lower end of the plug 1 is inserted. The cup 17 may or may not be cemented to the plug 1. After 90 the bottle is filled the entire device is placed in the neck and is made secure with any preferred cement.

Having now fully described our invention, what we claim as new, and desire to secure by 95 Letters Patent of the United States, is—

1. In a non-refillable bottle, a tubular plug adapted to fit within the bottle-neck, an integral baffle-plate within the upper portion of said plug, said baffle-plate having ports 100 therein, said ports being bounded by the inner wall of said plug, and an annular flange

projecting inwardly from said plug below said baffle-plate; substantially as described.

2. In a non-refillable bottle, a tubular plug adapted to fit within the bottle-neck, a piece 5 7 fitting within the lower end of said plug, a valve seated upon said piece 7, said valve having a cup-like chamber therein, and an inwardly-projecting flange slightly above said valve; said flange being integral with said tubular plug, substantially as described.

3. In a non-refillable bottle, a cup 17 having a concentric opening in its bottom, a disk valve covering said opening and a tubular piece 7, within said cup above said valve, 15 said piece 7 having an external flange 8, and a crenelated lower edge; substantially as described.

4. In a non-refillable bottle, a cup 17, having a concentric opening in its bottom, a disk 20 valve covering said opening, said valve having peripheral recesses therein, and a tubular piece 7 within said cup above said valve, said piece 7 having an external flange 8 and depending spaced projections 9', substantially 25 as described.

5. In a non-refillable bottle, a tubular plug, a fluted valve mounted therein, the lower portion of said valve being approximately

conical in shape, a tubular piece 7 fitting within the lower end of said plug, said valve 30 being seated upon the upper edge of said piece 7, a cup 17 below said plug the bottom of said cup having a concentric opening therein, a disk valve covering said opening, and the lower edge of said piece 7 having spaced 35 notches therein; substantially as described.

6. The combination of a tubular plug adapted to fit within a bottle-neck, a piece 7 fitting within the lower end of said plug, a valve 13 seated upon said piece 7, an inwardly-projecting flange 6 slightly above said valve, a baffle-plate 3 slightly above said flange, a cup 17 having its upper portion embracing the lower portion of said plug, the bottom of said cup having a central opening therein, and a 45 disk valve seated over said opening, the lower edge of said piece 7 being crenelated and slightly above said disk valve; substantially as described.

In testimony whereof we affix our signatures in the presence of two witnesses.

ANNE A. DONHAM.
ISAAC D. PEARCE.
